UNITED STATES PATENT OFFICE

134,071

DESIGN FOR AN ADVERTISING SIGN

Philip F. Wendell, La Crescent, Minn.

Application July 29, 1942, Serial No. 107,625

Term of patent 3½ years

To all whom it may concern:

Be it known that I, Philip F. Wendell, a citizen of the United States, residing at La Crescent, in the county of Houston and State of Minnesota, have invented a new, original, and ornamental Design for an Advertising Sign, of which the following is a specification, reference being had to the accompanying drawing, forming part thereof.

I claim:

The ornamental design for an advertising sign, substantially as shown.

P. F. WENDELL.
